SHOE BOTTOM COATING MACHINE

Charles C. Bell, Marblehead, Mass., assignor to
United Shoe Machinery Corporation, Flemington, N. J., a corporation of New Jersey

Application May 19, 1941, Serial No. 394,067

3 Claims. (Cl. 12—80)

This invention relates to coating machines and is herein illustrated as embodied in a machine for applying an adhesive to the overlasted upper upon the bottom of a shoe in preparation for the attachment of a sole thereto by cement.

In the machine for applying cement to the overlasted upper upon the bottoms of shoes which is illustrated in Letters Patent of the United States No. 2,177,666, granted October 31, 1939, upon the application of W. L. MacKenzie et al., the shoe is held in inverted position as it is presented to a depending, coating-applying nozzle with the side of the shoe resting against a driven feed roll. The operation is commonly started near the breast line on one side of the shoe and proceeds along the margin of the overlasted upper around the periphery of the bottom of the shoe to a similar position on the other side. As the operator presents a shoe to such a machine, it is necessary that he shall hold the bottom of the shoe substantially parallel to the contacting end of the nozzle and that he shall raise the work firmly into contact with the depending nozzle to cause the latter to apply a substantially uniform pressure across the width of the margin which is to be coated. The nozzle illustrated in that patent is made up of a series of hinged applying members which are spring-pressed into contact with the work. Most operators will stand at the side of the machine where they will be able to look along the bottom of the shoe and see whether the upward pressure has deflected the applying members substantially uniformly so that the coating will be evenly applied. It has been found, however, that some operators prefer to stand at the end of the machine, looking at the nozzle from the side, and then it is less easy for them to determine whether or not the shoe is properly held. Furthermore, the shoe, as it is turned to present the toe end thereof to the nozzle, projects outwardly from the machine toward the operator and must be manipulated so as not to collide with his body. There is a tendency, therefore, in turning the shoe, to tilt it more than is intended in order to avoid such collision and, when this is done, the upward pressure against the inner applying members of the nozzle is unduly severe, with the result that either the nozzle members are broken or, at the very least, the tubes which supply those members are bent beyond their elastic limit.

Accordingly, it is an object of this invention to provide an improved machine having an adjustable support for the nozzle which will per-

mit the latter to be tilted to accommodate the habits and stature of the operator.

To this end and in accordance with features of the invention, the illustrated machine is provided with a nozzle support having a curved slot to permit adjustment of the nozzle carrier. As illustrated, this slot is centered approximately at the edge of the inner corner of the nozzle adjacent to the feed roll so that changes in the nozzle position will disturb its relation to other parts of the machine as little as possible.

These and other features of the invention will be best understood from a consideration of the following specification taken in connection with the accompanying drawings, in which

Fig. 1 is a side elevation of the work-contacting elements of the machine and the nozzle-supporting bracket; and

Fig. 2 is an angular view taken from the other side of the machine.

As in the patented machine, there is a frame 10 having, pivotally secured near the top, a block 12 which may be adjusted heightwise against the tension of a spring (not shown) by means of a thumbscrew 14 and, in this block, there is a nozzle-carrying arm comprising a rod 16 and a slotted bracket 18 held on the end of the rod by a clamp screw 20. The rod 16 is locked in adjusted position in the block 12 by means of a set screw 22 having a pointed lower end received in a groove 24 in the upper side of the rod and, in setting up the machine, the rod may be adjusted in and out with respect to the frame.

The slotted bracket 18 is provided with a curved recess 30 adapted to receive a supplemental projection on a nozzle support 32 which is held in adjusted position therein by means of a pair of clamp bolts 34 extending through a curved slot 36 which opens into this groove 30.

The nozzle support 32 has a forked lower end provided with notches 38 (Fig. 2) for the reception of a nozzle block 40. The block 40 is held in position in the bracket 32 by a pivoted clamp member 42 urged into clamping position by a thumbscrew 44. The nozzle is made up of a series of applying members 48 each of which has an outlet opening in its work-contacting end surface. These members are supported on a pivot pin 52 and are held down in the illustrated normal position by means of spring fingers 54. They may be raised slightly by contact with the overlasted upper U on the bottom of a shoe S as the bottom is brought into operating position with its side face pressed against the periphery of a driven feed wheel 60. The coating material is supplied to the

individual outlet openings by means of a series of capillary tubes 56 (Fig. 2) and the nozzle is protected against damage by suitably shaped guards shown at 58 and 59. These tubes are supplied through a shut-off valve 62 from a pump, not shown, which delivers the cement under pressure through a flexible hose 64 whenever the rod 66, with its universal joints, is turned by a treadle connection, not shown.

The center of curvature of the groove 30 and of the slot 36 lies approximately at a point 70 at the inner corner of the portion of the nozzle which coats the outer part of the marginal band on the overlasted upper U. From another point of view, this center 70 lies in a line extending substantially parallel to the direction of feeding movement and at that corner of the nozzle which is adjacent to the feed roll. As a consequence of this location, adjustments of the angular position of the nozzle will not substantially affect its relation to the feed roll which will contact the side of the shoe as desired.

If, then, the position of the nozzle bracket 32 is so selected that it is most convenient for the operator who is using the machine, there is less tendency upon the part of the operator to tilt the shoe either in such a direction as to carry it away from the nozzle or, on the other hand, to apply an undue upward thrust to the inner portion of the nozzle.

In the use of the machine, the overlasted upper U of the shoe S is presented to the depending nozzle at a point on the shoe which lies just to the rear of the heel breast line and then the shoe is moved with the help of the feed roll 60 to apply a band of cement along the margin of the bottom of the shoe forward to and around the toe end thereof and then back along the other side of the shoe to a point at the rear of the heel breast line. In so doing, if the position of the nozzle with respect to the bracket 18 is properly selected, there will be little danger of applying undue pressure to the applying members 48 so as to put a strain upon these members or to carry the tubes 56 beyond their elastic limit.

Having described the invention, what I claim as new and desire to secure by Letters Patent of the United States is:

1. In a machine for applying cement to the overlasted upper of an inverted shoe, a depending nozzle arranged to apply a band of cement to said overlasted upper, a feed roll positioned adjacent to the nozzle and arranged to engage the side of an inverted shoe presented to the nozzle, and a support constructed and arranged to hold said nozzle with its work-contacting surface in any one of a plurality of planes at an angle to the horizontal and intersecting each other along a line approximately at that corner of the nozzle which is adjacent to the feed roll.
2. In a machine for applying cement to the overlasted upper of an inverted shoe, a depending nozzle arranged to apply a band of cement to said overlasted upper, a feed roll positioned adjacent to the nozzle and arranged to engage the side of an inverted shoe presented to the nozzle, and a support for said nozzle mounted on the machine for angular adjustment of the work-contacting surface of the nozzle about an axis substantially parallel with the direction of feeding movement and adjacent to that portion of the nozzle which coats the outer part of the marginal band whereby the plane of the bottom of the shoe as it is presented to the machine may be positioned to suit the operator.
3. In a machine for applying cement to the overlasted upper of an inverted shoe, a depending nozzle arranged to apply a band of cement to said overlasted upper, said nozzle comprising a plurality of pivoted members, a feed roll positioned adjacent to the nozzle and arranged to engage the side of the inverted shoe presented to the nozzle, and means for supporting said nozzle on the machine comprising coacting members one of which is provided with a slot curved about a point adjacent to the shoe-contacting end of the nozzle and the other of which has a locking member extending through the slot.
